US00D779538S

(12) **United States Design Patent** (10) **Patent No.:** **US D779,538 S**
Jin et al. (45) **Date of Patent:** **** Feb. 21, 2017**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Jung Sun Jin**, Seoul (KR); **Sook-Kyung Lee**, Gwangmyeong-si (KR); **Min Wook Na**, Suwon-si (KR); **Ji-Hye Myung**, Seoul (KR); **Youngil Oh**, Gwacheon-si (KR); **Hankyoung Jeon**, Seongnam-si (KR)

(73) Assignee: **SAMSUNG ELECTRONICS CO., LTD.**, Suwon-si (KR)

(**) Term: **15 Years**

(21) Appl. No.: **29/547,406**

(22) Filed: **Dec. 3, 2015**

(30) **Foreign Application Priority Data**

Jul. 29, 2015 (KR) 30-2015-0038313
(51) **LOC (10) Cl.** **14-04**
(52) **U.S. Cl.** **D14/486**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The dashed broken lines that show a display screen or portion thereof and text form no part of the claimed design. The dot-dash broken lines that show a boundary line forms no part of the claimed design.

1 Claim, 1 Drawing Sheet
